UNITED STATES PATENT OFFICE

JOSEPH APPLETON, OF OSHKOSH, WISCONSIN, ASSIGNOR TO SIMPLICITY MANUFACTURING COMPANY, OF PORT WASHINGTON, WISCONSIN, A CORPORATION OF WISCONSIN

PORTABLE BORING AND GRINDING MACHINE

Continuation of application Serial No. 676,587, filed November 23, 1923. This application filed February 18, 1929. Serial No. 340,995.

The invention relates to a portable boring and grinding machine.

The boring and grinding machine to which the invention applies in particular is illustrated and described in the patent to Nels A. Nelson No. 1,708,798 April 9, 1929, and the patent to Joseph Appleton No. 1,708,822 April 9, 1929, and has a horizontal base for attachment to an engine cylinder, a vertical standard carried by the base, a tubular outer shaft arranged in the standard to rotate and slide therein, a feed screw arranged alongside and connected to the outer shaft to support the same and to move it vertically, an inner shaft carried in the outer shaft and rotatable independently thereof to drive a grinding tool, a rotary driver arranged alongside the outer shaft, and a drive connecting the inner shaft and the driver and movable with the inner shaft along the driver.

The present application is a continuation of my application filed November 23, 1923, Serial No. 676,587.

An object of the invention is to move the inner shaft drive positively in unison with the vertical movement of the inner shaft.

Another object is to provide an improved carrier for the outer shaft.

Another object is to provide an efficient belt tightener for the inner shaft drive.

Another object is to facilitate the changing and adjustment of tools when the machine is in operative position.

According to the invention as it is ordinarily embodied, the outer shaft is supported and moved vertically by a shaft carrier which also supports the inner shaft drive and moves the same positively in unison with the vertical movement of the inner shaft.

The invention further provides an idler pulley on the shaft carrier to keep the belt taut.

The invention further provides an opening or passageway in the frame of the machine to permit the tools to be changed or adjusted when the machine is in operative position.

A machine embodying the invention is illustrated in the accompanying drawing in which the views are as follows:

Fig. 1 is a side elevation of the machine with parts in section.

Fig. 2 is a sectional plan on line 2-2 of Fig. 1.

Fig. 3 is a plan view of the shaft support. 55

Fig. 4 is a side elevation of the shaft support.

Fig. 5 is a section on line 5-5 of Fig. 3.

Fig. 6 is a section on line 6-6 of Fig. 3.

Fig. 7 is a section on line 7-7 of Fig. 3. 60

Fig. 8 is a detail of the idler pulley.

Fig. 9 is a vertical section through a boring tool.

The machine has its mechanism carried by a support or frame having a horizontal base 1 for attachment to an engine cylinder, a vertical standard 2 which may be formed integral with the base, and an upper frame 3 arranged upon the standard. 65

Lateral openings 4 and 5 are provided in the frame at or near the junction of the standard and the base to permit access to the tools and the opening 4 is of sufficient size to permit the tools to be changed when the machine is mounted upon a cylinder. 70

A rotatable and slidabile outer shaft 6 is journaled in a bearing in the standard and threaded at its lower end to carry either a boring tool or a grinding tool.

An inner shaft 7 is arranged in the outer shaft to drive the grinding tool and supported therein by thrust bearings 8 which are carried by the outer shaft. 80

The machine is driven by an electric motor 9 which is arranged vertically on the standard and has its shaft connected to a vertical shaft 10 by a flexible joint 11. 85

The outer shaft is rotated by a gear 12 which is splined thereon, held against vertical movement by the frame, and driven from the shaft 10 through a gear train 13.

The shaft 10 is connected to and rotates a driving shaft 14 which is arranged alongside the outer shaft and has its upper end journaled on a pin bearing 15 carried by the top 16 of the upper frame. 90

The inner shaft is driven from the driving shaft 14 by a belt 17 which connects a pulley 18 carried by the inner shaft with a driving pulley 19 splined on the driving shaft. 100

The driving shaft 14 has a keyway 20 extending substantially its entire length to permit the driving pulley 19 to move therewith as the inner shaft moves vertically.

5 The outer and inner shafts are supported and moved vertically by a feed screw 21 journaled in the top 16 and the bottom 22 of the upper frame 3 alongside the outer shaft and connected thereto by a shaft carrier which is threaded on the feed screw and has a thrust bearing connection with the flanged cap or head 23 of the outer shaft.

10 The shaft carrier has a shaft support 24, to carry the outer shaft and the driving pulley, and a feed nut 25 which is threaded on the feed screw and journaled in a U-shaped extension or bearing 26 on the shaft support.

15 The feed nut has a flange 27 on its lower end and a toothed wheel 28 on its upper end between which the bearing 26 has a running fit to fix the shaft support for vertical movement with the feed nut.

20 The shaft support 24 has a bore 29, in which the top of the outer shaft is rotatable, and a counterbore 30 surrounded by flanges 31 and 32 between which the flange of the head 23 has a running fit.

25 The shaft support is divided on the center-line of the bore 29 into two parts 33 and 34 to permit the same to be attached to the head 23 and the two parts are connected by bolts 35.

30 The driving pulley 19 has a sleeve 36 formed integral with its hub and adapted to rotate in a U-shaped extension or bearing 37 which is carried by the part 34 and has a running fit between the hub of the driving pulley and a collar 38 secured on the sleeve 36.

35 The flanges 31 and 32 form a thrust bearing for the flange of the head 23, the flange 27 and the toothed wheel 28 fix the shaft support for vertical movement with the feed nut, and the hub of the driving pulley and the collar 38 fix the driving pulley for vertical movement with the shaft support, thus holding 40 the feed nut, the outer shaft, and the driving pulley in fixed relation to one another and positively moving the driving pulley along the driving shaft as the outer and the inner shafts are moved vertically.

45 50 The flanged head 23 of the outer shaft carries a pin 39 which engages the teeth 40 of the toothed wheel 28 in succession and rotates the feed nut to move the same along the feed screw and advance the outer and inner shafts a predetermined distance during each revolution of the outer shaft.

55 60 The outer and inner shafts may be raised and lowered manually by turning a hand crank 41 which is attached to the upper end of the feed screw and provided with a locking screw 42 to hold the crank and the feed screw against turning when the machine is in operation.

65 70 The tension of the belt 17 may be adjusted by a belt tightener which has a supporting

75 arm 43 held in adjusted positions in the part 34 by a set screw 44 and carrying a shaft 45 upon which an idler pulley 46 is arranged for engagement with the belt.

80 The idler pulley 46 may be lubricated through a passageway 47 which is formed in the arm 43 and the shaft 45 and threaded at its outer end to receive a grease cup 48.

85 The grinding tool has a tool head 49, which is threaded at its upper end for attachment to the lower end of the outer shaft 6, and a bearing 50 which is pivoted on the tool head eccentric to the axis thereof and carries a grinding wheel 51.

90 The grinding wheel is driven from the inner shaft 7 by a gear train 52 and adjusted eccentrically to the tool head 49 by an adjusting mechanism 53, as more fully set forth in Patent No. 1,708,822 April 9, 1929.

95 The boring tool has a tool head 54 which is threaded at its upper end for attachment to the lower end of the outer shaft and carries a set of boring cutters 55 which abut the conical end of an adjusting screw 56 threaded in the tool head 54.

100 105 The adjusting screw 56 may be rotated in the tool head 54 by a wrench 57 to adjust the cutters 55 and is provided with a central bore 58 to accommodate the end of the wrench 57 when the cutters are being adjusted and to accommodate the lower end of the inner shaft 7 when the boring tool is attached to the outer shaft.

110 115 A limit switch 59 is attached to the upper frame 3 in selected positions and connected in circuit with the motor 9 to stop the same when the boring tool or the grinding tool has been advanced to a predetermined limit.

120 125 A switch actuator 60 is pivoted on the base of the switch and extends through the upper frame into the path of the feed nut 25 which engages it and opens the switch when the tool reaches the limit previously determined.

130 135 The machine set forth herein may be modified in various ways without departing from the invention embodied therein and hereafter claimed.

140 145 The invention is claimed as follows:

1. A boring and grinding machine comprising a portable frame having a horizontal base and a vertical standard, a rotatable and slideable outer shaft arranged in said standard, a drive to rotate said outer shaft, a shaft support to carry said outer shaft, means to move said shaft support vertically, an inner tool shaft carried in said outer shaft, a rotary driver arranged alongside said outer shaft, and a drive connecting said inner shaft and said driver and moved positively along said driver by said shaft support in unison with the vertical movement of said shafts. 150 155 160 165 170 175 drive connected to said outer shaft and having said outer shaft slideable relatively thereto, a shaft support to carry said outer shaft, means to move said shaft support vertically, an inner tool shaft carried in said outer shaft, 5 a rotary driver arranged alongside said outer shaft, and a drive connecting said inner shaft and said driver and moved positively along said driver by said shaft support in unison with the vertical movement of said shafts.

3. A boring and grinding machine comprising a portable frame having a horizontal base and a vertical standard, a rotatable and 15 slideable outer shaft arranged in said standard, a drive to rotate said outer shaft, an inner shaft arranged in said outer shaft to drive a tool and carried by said outer shaft, a feed screw arranged alongside said outer shaft, a shaft carrier supported by said feed screw and connected to said outer shaft to support the same, means to move said shaft carrier along said feed screw, a rotary driver arranged alongside said outer shaft, and a 20 drive connecting said inner shaft and said driver and positively moved by said shaft carrier along said driver.

4. A boring and grinding machine comprising a portable frame having a horizontal base and a vertical standard, a rotatable and 25 slideable outer shaft arranged in said standard, a drive to rotate said outer shaft, an inner shaft arranged in said outer shaft to drive a tool and carried by said outer shaft, a feed screw arranged alongside said outer shaft, a shaft carrier supported by said feed screw and having a thrust bearing connection with said outer shaft to support the same, means to move said shaft carrier along said feed screw, a rotary driver arranged alongside said outer shaft, a drive connecting said inner shaft and said driver and positively moved by said shaft carrier along said driver.

5. A boring and grinding machine comprising a vertical outer shaft having independent rotary and axial movements, a feed screw arranged alongside said shaft, a shaft carrier supported by said feed screw and connected to said shaft to support the same, an inner shaft arranged in said outer shaft to drive a tool and carried by said outer shaft, a rotary driver arranged alongside said outer shaft, a drive connecting said inner shaft and said driver and carried by said shaft carrier along said driver, and means to move said shaft carrier along said feed screw.

6. A boring and grinding machine comprising a vertical outer shaft having independent rotary and axial movements, a feed screw arranged alongside said shaft, a shaft carrier supported by said feed screw and having a thrust bearing, a flanged head carried by said outer shaft and engaging said bearing to be supported and moved vertically thereby, an inner shaft arranged in said outer

shaft to drive a tool and carried by said outer shaft, a rotary driver arranged alongside said outer shaft, a drive connecting said inner shaft and said driver and carried by said shaft carrier along said driver, and means to move said shaft carrier along said feed screw.

7. A boring and grinding machine comprising a vertical outer shaft having independent rotary and axial movements, an inner shaft arranged in said outer shaft to drive a tool and carried by said outer shaft, a rotary driver arranged alongside said outer shaft, a drive connecting said inner shaft and said driver and movable with said inner shaft along said driver, a feed screw arranged alongside said outer shaft, a shaft carrier supported by said feed screw to support said outer shaft and said inner shaft drive and hold the same in fixed relation to each other, and means to move said shaft carrier along said feed screw.

8. A boring and grinding machine comprising a vertical outer shaft having independent rotary and axial movements, an inner shaft arranged in said outer shaft to drive a tool and carried by said outer shaft, a rotary driver arranged alongside said outer shaft, a drive connecting said inner shaft and said driver and movable with said inner shaft along said driver, a feed screw arranged alongside said outer shaft, a feed nut threaded on said feed screw, a shaft support carried by said feed nut and connected to said outer shaft and said inner shaft drive to support the same, and means to rotate said nut and move the same along said feed screw.

9. A boring and grinding machine comprising a vertical outer shaft having independent rotary and axial movements, a feed screw arranged alongside said shaft, a shaft carrier supported by said feed screw and connected to said shaft to support the same, an inner shaft arranged in said outer shaft to drive a tool and carried by said outer shaft, a driven pulley carried by said inner shaft, a driving shaft arranged alongside said outer shaft, a driving pulley splined on said driving shaft and fixed for vertical movement with said shaft carrier, a belt connecting said driving pulley and said driven pulley, and means to move said shaft carrier along said feed screw.

10. A boring and grinding machine comprising a vertical outer shaft having independent rotary and axial movements, a feed screw arranged alongside said shaft, a shaft carrier supported by said feed screw and connected to said shaft to support the same, an inner shaft arranged in said outer shaft to drive a tool and carried by said outer shaft, a driven pulley carried by said inner shaft, a driving shaft arranged alongside said outer shaft, a driving pulley splined on said driving shaft and fixed for vertical movement with said shaft carrier, a belt connecting said driving pulley and said driven pulley, a belt

- tightener arranged on said shaft carrier and engaging said belt to adjust the tension thereof, and means to move said shaft carrier along said feed screw.
- 5 11. A shaft carrier for a boring and grinding machine comprising a shaft support having an annular thrust bearing to support a vertical shaft for rotation therein and a second bearing to receive a rotary driver and 10 means to support said carrier from a feed screw.
12. A shaft carrier for a boring and grinding machine comprising a shaft support having an annular thrust bearing to support a 15 vertical shaft for rotation therein, a bearing carried by said support to fix a rotatable part of the machine for vertical movement with said support, and means to support said carrier from a feed screw.
- 20 13. A shaft carrier for a boring and grinding machine comprising a shaft support having two separable parts and a thrust bearing at the junction of said parts to support a vertical shaft for rotation therein, means to 25 fasten said parts together, and means to support said carrier from a feed screw.
14. A shaft carrier for a boring and grinding machine comprising a shaft support having two separable parts and a thrust bearing 30 at the junction of said parts to support a vertical shaft for rotation therein, means to fasten said parts together, a bearing carried by one of said parts to fix a rotatable part of the machine for vertical movement with said 35 support, and means to support said carrier from a feed screw.
15. A shaft carrier for a boring and grinding machine comprising a shaft support having two separable parts and a thrust bearing 40 at the junction of said parts to support a vertical shaft for rotation therein, means to fasten said parts together, a bearing carried by one of said parts, a feed nut arranged to rotate in said bearing and held against 45 axial movement therein to support said carrier from a feed screw, and a bearing carried by the other of said parts to fix a rotatable part of the machine for vertical movement with said carrier.
- 50 16. A shaft carrier and belt tightener for a boring and grinding machine comprising a shaft support adapted to be supported from a feed screw and having a thrust bearing to support a vertical shaft for rotation therein, a bearing carried by said support to fix a driving pulley for vertical movement with said support, and an idler pulley carried by said support and adapted to engage a belt.
- 60 17. A shaft carrier and belt tightener for a boring and grinding machine comprising a shaft support having a thrust bearing to support a vertical shaft for rotation therein, a bearing carried by said support, a feed nut arranged to rotate in said bearing and held 65 against axial movement therein to support said carrier from a feed screw, a second bearing carried by said support to fix a driving pulley for vertical movement with said carrier, and an idler pulley carried by said support and adapted to be secured in adjusted positions.
- 70 18. A shaft carrier and belt tightener for a boring and grinding machine comprising a shaft support adapted to be supported from a feed screw and having a thrust bearing to support a vertical shaft for rotation therein, a bearing carried by said support to fix a driving pulley for vertical movement with said support, a rod arranged in said support, a pulley shaft carried by said rod, an idler pulley arranged on said shaft to engage a belt, and means to adjust said rod transversely of said support.
- 75 19. A boring and grinding machine comprising a portable frame having a horizontal base and a vertical standard, a rotatable and slideable outer shaft arranged in said standard and adapted to carry either a boring tool or a grinding tool at its lower end, said frame having an opening near the bottom of said standard to permit said tools to be passed therethrough, a drive to rotate said outer shaft, an inner shaft arranged in said outer shaft to drive a tool and carried by said outer shaft, a rotary driver arranged alongside said outer shaft, a drive connecting said inner shaft and said driver, means to move said shafts vertically, and means to move said inner shaft drive positively along said driver in unison with the vertical movement of said inner shaft.
- 80 100 20. A boring and grinding machine comprising a portable frame having a horizontal base and a vertical standard, a rotatable and slideable outer shaft arranged in said standard and adapted to carry either a boring tool or a grinding tool at its lower end, said frame having an opening near the bottom of said standard to permit said tools to be passed therethrough, a motor carried by said frame to rotate said outer shaft, an inner shaft arranged in said outer shaft to drive a tool and carried by said outer shaft, a rotary driver arranged alongside said outer shaft and driven by said motor, a drive connecting said inner shaft and said driver, means to move said shafts vertically, means to move said inner shaft drive positively along said driver in unison with the vertical movement of said inner shaft, and a limit switch arranged in adjusted positions to control said motor and stop the machine as said tool reaches a predetermined limit.
